BIN LEVEL SWITCH

Charles W. McMath, Fort Worth, Tex.

Application September 25, 1950, Serial No. 186,663

6 Claims. (Cl. 200—52)

1

This invention relates to switches and more particularly to pressure switches.

In many applications pressure responsive switches are employed to indicate or warn when a tank or bin is filled to a predetermined level. For example, such switches are employed to give warning when a gravel bin is filled with gravel to its capacity. The switches may also be employed to stop operation of loading equipment, which fills the bin with the gravel or other material, when the bin is filled to a certain level. Such switches should be adjustable in order that they may be adjusted to operate properly when attached to tanks or bins filled with different materials which exert different pressures on the switches. Moreover, the switches should be easily assembled and disassembled to facilitate maintenance and should be rugged in construction to withstand rough usage to which they are subjected.

Accordingly, it is an object of my invention to provide a new and improved switch.

It is another object of my invention to provide a new and improved pressure responsive switch.

It is another object of my invention to provide a new and improved pressure responsive switch for use with tanks or bins to indicate when the tank or bin is filled or emptied.

It is still another object of my invention to provide a new and improved pressure responsive switch having a diaphragm which is subjected to a very narrow range of movement.

Briefly stated, my new and improved pressure responsive switch comprises a base section adapted to be connected to a tank, bin or other receptacle or conduit and extend through an aperture in a wall thereof. A diaphragm is secured to the base section and has an inner surface subjected to the pressure exerted by the material or substance contained in the tank, bin or conduit. In order to protect the diaphragm, a backing plate is provided which abuts the outer surface of the diaphragm. A mechanical linkage connects the backing plate to a micro-switch. An adjustable spring is operatively associated with the linkage to provide a means selectively to vary the pressure to which the diaphragm must be subjected to actuate the micro-switch.

For a better understanding of my invention, reference may be had to the following description taken in connection with the accompanying drawing and its scope will be pointed out in the appended claims.

Figure 1 is a sectional view of the switch shown in its operational environment;

2

Figure 2 is a side elevation of the switch;

Figure 3 is an exploded view of the switch;

Figure 4 is a perspective view of one of the components of the switch; and,

Figure 5 is a perspective view of another of the components of the switch.

Referring now to the drawing, the switch comprises an annular base section 10 having an annular central portion 11 which is adapted to project through a suitable aperture in a wall 12 of a receptacle or conduit. An outwardly extending flange 13, integral with and at one end of central portion 11, is provided with a plurality of spaced apertures through which are adapted to extend screws 14 which engage in suitable tapped holes in wall 12. An annular resilient gasket 15 of rubber or other suitable material is interposed between flange 13 and wall 12. Gasket 15 is provided with a plurality of spaced apertures 16 which register with the apertures in flange 13 and wall 12.

An inwardly extending annular flange 16 integral with and at the other end of central portion 11 is provided with an inner bevel surface 17 and a plurality of spaced threaded apertures 18 between central portion 11 and beveled surface 17. A diaphragm clamping ring 19 is also provided with a beveled surface 20 which cooperates with beveled surface 17 to secure a disc shaped diaphragm 21 to flange 16 of base section 10. Ring 19 is secured to flange 16 by screws 22 which extend through suitable apertures 23 in ring 19 and engage threaded apertures 18 of flange 16. Ring 19 and flange 16 cooperate to maintain the central portion of diaphragm 21 in a plane normally parallel to the outer surface 24 of flange 16. Diaphragm 21 may be made of a relatively stiff or slightly yielding material such as reinforced rubber, or a metal sheet of brass, copper, steel or other suitable material since very little diaphragm movement is needed in normal operation of the device.

The complementary beveled surfaces 17 and 20 of the flange 16 and ring 19, respectively, are effective to create the required uniform tension on the diaphragm 21 during its installation and to maintain such tension subsequent to installation.

A disc shaped cover plate 25 is secured to base section 10 by means of screws 26 which extend through suitable apertures in plate 25 and engage in threaded holes 27 in base section 10. A supporting block 28 having spaced legs 29 and 30 is secured to plate 25 by a screw 31 which extends through a suitable aperture in plate 25

and engaging in a threaded hole 32 in the upper end of block 28. A lever 33 is pivotally secured between legs 29 and 30 by means of a pin 34 which extends through registering apertures 35, 36 and 37 in legs 29, 30 and lever 33, respectively.

A ribbed backing plate 38 is secured to the free end of lever 33 by means of a screw 39 which extends through central apertures in backing plate 38 and a spacing sleeve 40 and engages in a threaded aperture 41 in lever 33. The upper end of screw 39 is spaced a very short distance from cover plate 25 to limit the movement of backing plate 38, and therefore of diaphragm 21, toward cover plate 25. Also secured to the inner surface of cover plate is a spring supporting block 42 which is secured to plate 25 by a screw 43. Block 42 is provided with a slot in which is rigidly secured, by soldering or any other conventional means, one end of a leaf spring 44. The free end of leaf spring 44 abuts and bears against lever 33 yieldingly to urge the free end of lever 33 away from cover plate 25. An adjusting screw 45 extends through a threaded aperture in cover plate 25 and bears against spring 44 to vary the force spring 44 exerts on lever 33. A lock nut 46 is provided for screw 45 to lock it in a desired position.

Intermediate its ends, lever 33 is provided with a threaded aperture in which is engaged a screw 47 which is disposed to engage the push rod 48 of a conventional micro-switch 49 when lever 33 is moved pivotally toward plate 25. The micro-switch 49 is secured in a housing comprising sections 50 and 51 by means of pins 52 and 53 which extend through suitable apertures in sections 50, 51 and micro-switch 54. The housing sections 50 and 51 are secured to each other by means of bolts 55. Each section 50 and 51 is provided with a flange 56 provided with a pair of apertures through which extend screws 57 which engage in threaded holes 58 in cover plate 25 to secure the sections 50 and 51 to plate 25. Cover plate 25 is also provided with an aperture 59 through which extend in telescoped relation the push rod 48 of micro-switch 49 and its sleeve 60. The housing sections 50 and 51 are provided with apertures 61 and 62 through one of which may extend the conductors 63 and 64 which are connected to micro-switch 49. Conductors 63 and 64 may be connected to any suitable electric circuit to control a warning or indicating device, a motor, or any other desired electrically controlled element.

In operation, the above described pressure responsive switch is preferably secured to a vertical wall 12 of a tank, bin or conduit which wall may be vertical or any slope greater than the angle of repose of the material in the bin or the like. When the bin or the like is filled to such a height with material that the material abuts and exerts a force on diaphragm 21, the diaphragm 21 will yield inwardly toward plate 25 provided that the force exerted by the material on diaphragm 21 overcomes the force exerted by spring 44 on lever 33 as well as the force needed to flex diaphragm 21 and actuate micro-switch 49. It will be obvious that screw 45 will be employed to make the spring 44 exert an appropriate pressure on lever 33. When diaphragm 21 yields and moves, backing plate 38 will also move pivoting lever 33 toward plate 25. During this movement of lever 33, screw 47 will move push rod 48 to actuate micro-switch 49 to make or break an electric circuit. The pivotal movement of lever 33 is limited since screw 39 will abut plate 25 after

lever 33 has moved a predetermined distance. When the material in the bin falls to a level in which it no longer exerts sufficient pressure on diaphragm 21, the force exerted by spring 44 will move backing plate 38 to its original position illustrated in Figure 1. Diaphragm 21 will move back to its original position due to its resiliency.

It will be noted that diaphragm 21 does not extend inwardly beyond flange 16 of base section 10 so that the material in the bin does not lie in the path of movement of the material to impede its movement and at the same time increase the abrasive wear of diaphragm 21. Moreover, the method of securing diaphragm 21 to base section 10 obviates the need for bolt holes which would weaken the diaphragm 21. The backing plate 38 protects diaphragm 21 from excessive force such as might result from the falling of rocks against diaphragm 21 in gravel bin installations.

The mechanical linkage is very simple having only one pivot thus reducing friction losses to a minimum. In addition, the range of movement of diaphragm 21 is quite narrow permitting the use of a relatively taut diaphragm which eliminates sagging and the resulting tendency of the diaphragm to trap or hold material in a hollow or fold caused by the sagging.

The arrangement and connection of parts of the above described pressure responsive switch facilitates installation and maintenance. Base section 10 can be secured to wall 12 from the outside of the bin thus obviating the necessity of having access to the interior of the bin. The micro-switch 49 can be removed for inspection, repair or replacement without disturbing the other components of the system since screw 47 merely bears against push rod 48 of the switch. Should adjustment or repair of the mechanical linkage be necessary, cover plate 25 only need be removed since diaphragm 21 is not connected to backing plate 38 or any part of the mechanical linkage.

While I have described and illustrated a preferred embodiment of my invention, it will be obvious that various changes and modifications can be made without departing from my invention and I, therefore, aim in the appended claims to cover all such changes and modifications as fall within the true spirit and scope of my invention.

What is claimed is:

1. A pressure responsive device comprising a hollow base section; a resilient diaphragm secured to said base section and closing off one end of said base section; a cover plate secured to said base section and closing off the other end of said base section; a backing plate movably disposed in said base section and abutting said diaphragm; a lever having one end pivotally connected to said cover plate and the other end secured to said backing plate; means biasing said backing plate toward said diaphragm; a stop operatively associated with said backing plate for limiting movement of said backing plate toward said cover plate; and a switch mounted on said cover plate exteriorly of said base section, said cover plate being provided with an aperture, said switch having an operating member extending through said aperture into said base section, said operating member being operatively associated with said backing plate and responsive to movement of said backing plate toward said cover plate.

2. A pressure responsive device comprising a hollow base section; a resilient diaphragm se-

cured to said base section and closing off one end of said base section; a cover plate secured to said base section and closing off the other end of said base section; a backing plate movably disposed in said base section and abutting said diaphragm; a lever having one end pivotally connected to said cover plate and the other end secured to said backing plate; means biasing said backing plate toward said diaphragm; a stop operatively associated with said backing plate for limiting movement of said backing plate toward said cover plate; and a switch mounted on said cover plate exteriorly of said base section, said cover plate being provided with an aperture, said switch having an operating member extending through said aperture into said base section, said operating member being operatively associated with said lever and responsive to pivotal movement of said lever toward said cover plate.

3. A pressure responsive device comprising a hollow base section; a resilient diaphragm secured to said base section and closing off one end of said base section; a backing plate movably disposed in said base section and having one side abutting one side of said diaphragm, said backing plate substantially closing off said one end of said base section; a cover plate secured to said base section and closing off the other end of said hollow base section; a switch mounted on said cover plate exteriorly of said base section, said cover plate being provided with an aperture, said switch having an operating member extending through said aperture into said base section; a lever pivoted at one end to said cover plate and connected at its opposite end to the center of said backing plate and having engagement with said operating member for actuating said switch upon movement of said backing plate toward said cover plate, means biasing said backing plate toward said diaphragm and means for adjusting the tension on said biasing means.

4. A pressure responsive device comprising a hollow base section having an internally beveled flange on one end, a ring attached to the interior of said flange having a bevel corresponding to the bevel of said flange; a resilient diaphragm having its perimeter secured between the bevels of said ring and flange and closing off one end of said base section; a backing plate movably disposed in said base section and having one side abutting one side of said diaphragm, said backing plate being substantially equal in diameter to the diameter of the effective area of said diaphragm; a cover plate secured to said base sec-

tion and closing off the other end of said hollow base section; a switch mounted on said cover plate exteriorly of said base section, said cover plate being provided with an off-center aperture, said switch having an operating member extending through said aperture into said base section; a pivoted lever connecting said backing plate and said operating member for actuating said switch upon movement of said backing plate toward said cover plate; and means operatively associated with said lever for biasing said backing plate away from said cover plate.

5. In a pressure responsive device: a base section having a central aperture provided with an internally beveled flange, a ring having a bevel confronting the bevel of said flange, a resilient diaphragm secured at its perimeter between said ring and flange and closing off said central aperture at one end of said base section; a backing plate movably disposed in said base section relative to said central aperture and abutting said diaphragm, said backing plate having substantially the same radius as the effective area of said diaphragm; a cover plate secured to said base section and closing off said central aperture at the other end of said base section; a switch mounted on said cover plate exteriorly of said base section, said cover plate having an off-center aperture, said switch having an operating member extending through said aperture into said central aperture of said base section, a pivoted lever connecting said operating member and said backing plate for actuating said switch upon movement of said backing plate toward said cover plate and means for biasing said backing plate toward said diaphragm.

6. The device of claim 5, and a stop means operatively associated with said backing plate for limiting movement of said backing plate toward said cover member.
